(57) **CLAIM**

The ornamental design for a modular powered respirator, as shown and described.

DESCRIPTION

FIG. 1 is a front perspective view of my new design; FIG. 2 is a front view of the design thereof; FIG. 3 is a rear view of the design thereof; FIG. 4 is a right side view of the design thereof, the left side view being a mirror image thereof; FIG. 5 is a top view of the design thereof; and, FIG. 6 is a bottom view of the design thereof. The broken lines in the drawings depict portions of the modular powered respirator that form no part of the claimed design.

1 Claim, 6 Drawing Sheets
